RAILWAY TRAIN CONTROL SYSTEM

Original Filed June 4, 1913 2 Sheets-Sheet 2

Fig. 1. Section B.

UNITED STATES PATENT OFFICE.

ALBERT V. T. DAY, OF RYE, NEW YORK, ASSIGNOR TO THE UNION SWITCH AND SIGNAL COMPANY, OF SWISSVALE, PENNSYLVANIA, A CORPORATION OF PENNSYLVANIA.

RAILWAY-TRAIN-CONTROL SYSTEM.

Original application filed June 4, 1913, Serial No. 771,650. Renewed March 14, 1922, Serial No. 543,767. Patent No. 1,479,286, dated January 1, 1924. Divided and this application filed February 6, 1923. Serial No. 617,401.

To all whom it may concern:

Be it known that I, ALBERT V. T. DAY, a citizen of the United States, residing at Rye, in the county of Westchester and 5 State of New York, have invented certain new and useful Improvements in Railway-Train-Control Systems, of which the following is a specification.

My invention relates to that class of train 10 control apparatus and systems in which the movement of a railway train or vehicle is controlled in accordance with a signal, automatic brake, or other suitable train controlling means carried on a train or vehicle 15 and governed by suitable extraneous means or conditions, such as the position of a signal or the condition of a section of the track which the train or vehicle is approaching.

20 The present application is a division of my copending application filed on the 14th day of March, 1922, Serial No. 543,767, patented Jan. 1, 1924, No. 1,479,286, for railway train control systems, which latter 25 application is a renewal of my application filed on the 4th day of June, 1913, Serial No. 771,650.

In the accompanying drawings, Fig. 1 is 30 a diagrammatic view showing one form of system embodying my invention, this view comprising two sheets designated as Section A and Section B. Fig. 2 is an enlarged sectional view of a directional clutch employed in the apparatus shown in Fig. 1, and is 35 taken on the line II—II of Fig. 1.

Similar reference characters refer to similar parts in each of the views.

Referring to Fig. 1, the reference characters 2 and 2^a designate the track rails of 40 a single track over which traffic moves in both directions. A train, represented by a wheel U, is moving eastbound along this track. J and L are eastbound signals, and M and K are westbound signals. The 45 locomotive or car wheel U is geared to the vertical monitor shaft 355, extending upward through a bearing-lug formed in the bottom of the monitor casing. This shaft terminates flush with the upper surface of 50 the disc 356 secured on the upper end of this shaft and fixedly inserted into the

hollow hub of the bevel gear 503. The disc acts as a closing plate to retain the clutch balls disposed within the hub and surrounding the lower end of the monitor main shaft 55 358. The disc turns freely in the gear 503 in one direction, but is clutched thereto in the other direction by the clutching action of the balls, in the manner of the directional clutch shown in Fig. 2. The 60 lower end of the monitor main shaft 358 rests on the upper end of the monitor shaft 355, the two shafts being free to rotate in opposite directions. The monitor main shaft 358 carries another similar bevel gear 65 503^a above the gear 503 and also turning freely on the shaft 358 in one direction but clutched to the shaft in the other direction by the action of similar clutch balls, as indicated. Between these gears and meshing 70 with both of them is an intermediate bevel gear 503^b mounted on a horizontal shaft 60 extending through a bearing formed in the side of the casing. This intermediate gear transmits rotation from the lower bevel gear 75 503 to the upper bevel gear 503^a mounted on the monitor main shaft. Hence, no matter which way the shaft 355 turns as the locomotive or car travels in one direction or the other, the upper and lower bevel 80 gears mounted on the shaft 358 will always turn in opposite directions, one of them always transmitting rotation to the monitor main shaft in the direction of its indicating arrow, while the other gear turns freely on 85 the shaft in the opposite direction.

Mounted on the monitor main shaft 358 just above the bevel gears is a worm transmitting rotation to a worm wheel mounted 90 on a horizontal shaft extending across the casing and also carrying a worm located behind and meshing with the worm wheel 359 mounted on the vertical traveller shaft 360. Thereby the traveller shaft is always rotated slowly in the direction of its arrow 95 in exact proportion to the travel of the train in either direction.

Above the aforesaid worm on the main shaft 358 is formed a V-worm 361. A resetting traveller 362 mounted on the main 100 shaft consists in a sleeve surrounding the worm 361 with a clearance hole and having

a slot into which enters the vertical longer arm of an L-shaped clutch lever, the short horizontal arm of which constitutes an armature 363 co-acting with a clutch magnet 61 disposed above the armature and mounted on the under side of a horizontal arm extending from the sleeve 362. A similar arm 362^a extends horizontally from the upper end of the sleeve in the opposite direction and is bored with a clearance hole surrounding the traveller shaft 360 and normally rests on a collar 364 formed on this shaft to act as a lower stop for the re-setting traveller. The edge of the L-shaped re-setting clutch-lever is notched to fit the V-worm 361. The clutch magnet 61 is normally de-energized, but when its armature 363 is attracted, the notched edge of the upper arm of the clutch lever is held in mesh with the V-worm 361 so that the traveller will be gradually raised by the rotation of the worm while the clutch magnet is energized.

The regular monitor traveller 365 consists in a sleeve mounted with sliding clearance on the V-worm 366 cut on the upper end of the traveller shaft 360. This sleeve also has a slot into which enters the notched edge of the clutch dog 367 pivoted between lugs projecting horizontally from the upper end of the sleeve, and having its notched edge held normally in mesh with the V-worm by a flat spring 62 secured on the lower end of the sleeve. A horizontal arm 368 projects from the traveller sleeve and surrounds the monitor main shaft with a clearance hole. The graduating collar 369 is splined on the main shaft and supported by the traveller arm 368 and bears the lower end of the graduating spring 63.

The graduating spring 63 delivers an upward thrust upon the collar 126 which, by the equalizing lever 127, is transmitted equally to the thrust links 128 and thence to the monitor weights 370 and 371, so as to develop in the weights equal retentive efforts tending to maintain their respective contact buttons in rubbing engagement with the contact rings 132 and 133, respectively, mounted upon an insulating sleeve 131 which is mounted in the upper part of the monitor casing.

The monitor weights 370 and 371 are similarly formed and symmetrically mounted. They are bored with transverse holes 370^a and 371^a equi-distant from the monitor main shaft 358 as to have no effect on the gravity moment of the weights about their pivotal centers, but located at different elevations above their pivotal centers, so that the weight 370 with the lower bore will develop a greater centrifugal moment about its pivotal center than the weight 371 with the higher bore. Hence the weight 370 will fly outward at a definite percentage of the

greater speed which would be necessary to throw out the weight 371 with the same setting of the graduating spring 63.

A manual re-setting lever 452 is pivoted on a shaft 454 and extends through a slot 453 formed in the casing, the projecting end of the lever constituting a handle. The lever carries a pin *n'* which, when the handle is raised to the upper limit of the slot, will engage the traveller arm 368 and raise the traveller through a limited distance, thus effecting a partial reset and maintaining a low flat speed limit while the handle is thus held.

An insulating collar 374 is mounted on the outer end of the horizontal shaft 60 of the intermediate bevel gear, and is circumferentially grooved to receive a metallic flat ring from which protrudes the radial contact arm 375. As the insulating collar turns with the shaft, the ring slips in the circumferential groove but is subjected to sufficient friction drag to hold the contact arm 375 in engagement with one or the other of the diametrically opposite stop pins 376 and 377 mounted on the casing but suitably insulated therefrom, as indicated. Hence, the arm 375 will contact with one of the stop pins continuously during the movement of the locomotive in one direction, and will be transferred to contact with the opposite pin whenever the direction of locomotive travel is reversed.

The eastbound home signal at J is governed by the block J—L extending up to the next eastbound signals at L. The locomotive carries two contact shoes 399 and 400, connected respectively with the contact pins 376 and 377. When the locomotive is moving eastward, the contact pin 377 is out of connection with the contact arm 375, whereby this pin and the contact shoe 400 are entirely disconnected from the monitor apparatus so that no effect whatever can result from energizing the contact shoe 400, for instance, in passing over any westbound ramp rails, such as T, S, R, K'. When the shoe 399 rides on to the eastbound ramp rail L', the following re-setting circuit is closed: from the stationary battery 401, through the contacts controlled by the home signal at J, and thence through the wire 402, ramp rail L', contact shoe 399, connecting wire, contact pin 376, contact arm 375, connecting wire, clutch magnet 61 of the re-setting traveller, and thence through a wire grounded on the monitor casing and through the metallic parts of the apparatus to the wheel U, and thence through the upper track rail to the wire 403 and back to the opposite pole of the battery. The instant the foregoing circuit is closed, the clutch magnet raises the armature 363 of the L-shaped clutch-lever, thereby clutching the re-setting traveller to

the re-setting worm 361 and beginning an upward movement of this traveller which must be proportionate to the distance travelled by the train during the period of energization of the clutch magnet, that is to say, proportionate to the length of the ramp rail L' . When the shoe 399 leaves the ramp rail L' , the foregoing circuit is, of course, immediately broken, and the re-setting 5 traveller falls back against its bottom stop 364.

The diagram represents the regular speed-graduating monitor traveller 365 near its maximum elevation at the instant the re-setting traveller is beginning its rise in response to the ramp rail L' , since it is assumed that the regular traveller has been priorly re-set at a point farther back on the railroad to give the locomotive high speed 15 headway past the signals J. If we suppose, however, that the locomotive approached the signals J, with its regular traveller 365 in its lowest position resting on the re-setting arm 362^a of the re-setting traveller, 20 we may note that this re-setting arm would raise the regular traveller a definite distance equal to the rise of the re-setting traveller and hence proportionate to the length of the ramp rail L' , the clutch dog 25 367 of the regular traveller meanwhile slipping over its V-worm owing to the yielding of its retaining spring.

Now, if the graduating spring be so designed that it will be expanded to the 35 minimum or low speed limit when the regular traveller 365 stops in its lowest position against the re-setting arms 362^a, it will be noted that the clear headway afforded by the rise of the regular traveller 40 will be exactly proportionate to the length of the ramp rail L' , so that to re-set the traveller at successive signal posts for any clear headway whatever, it is only necessary to energize the contact shoe at each 45 signal post by a ramp rail proportionate to the clear headway indicated by the signals on that post. Hence, the clearing of the distant signal at J may serve to include an extension ramp rail N' in connection 50 with the wire 402, as indicated, the length of the ramp N' being such that the total length of the ramps L' and N' will be proportionate to the total clear headway from J to N corresponding to the home-and- 55 distant clear indication of the signals at J.

The parabolic speed-limit curves 404 and 405 indicate respectively the headways derived from the home clear and the home-and-distant clear indications of the signals 60 at J. The parabolic curve 406 represents the gradual rise of the speed limit from zero to the limit 404 or to the limit 405 as the traveller 369 is raised while the contact shoe wipes over the ramps L' and N' . Likewise the parabolic curve 407 represents the

rise of the speed limit derived from the ramps P and Q at the signals L, and the parabolic curve 408 represents the clear headway thus derived. The length of the ramp P is proportionate to the block L-N 70 and the total length of the ramps P, Q is proportionate to the clear headway indicated by the distant signal at L. If when the locomotive approaches the signals L, the traveller is falling in correspondence 75 with either limit curve 404 or 405, it will not have reached its lowest position when the contact shoe rides over the ramps P, Q, and hence will not be engaged by the re-setting traveller until the re-setting traveller has risen to the elevation at which its rising limit-curve 407 intersects either of the declining limit curves 404 or 405. If the locomotive passed home and distant 80 clear signals at J, it will be proceeding 85 under the stop limit 405 up to the intersection of this limit curve with the rising limit 407, after which the train will proceed subject to the rising limit-curve 407 to the end of the ramp rail Q, and thence 90 will be subject to the declining limit curve 408.

When the locomotive is moving in the reverse direction over the track, the contact arm 375 will be out of contact with the stop pin 376, thus leaving the eastbound contact shoe 399 entirely disconnected, while the westbound contact shoe 400 will be connected with the re-setting clutch magnet through the stop pin 377, thereby imparting 95 to the monitor at each westbound signal a re-set proportionate to the length of the ramp rail energized at that signal, the westbound ramp rails, of course, being proportionate in their lengths to the clear 100 headways indicated by their respective signals.

At Z is an interlocking point where the "main line" divides into "high speed," "medium speed," and "low speed" routes. 110 At Z', some distance in rear of Z, is a signal post carrying three distant signals respectively indicating the high speed, medium speed and low speed routes set up at Z. A ramp rail at Z' is divided by insulating 115 joints into three sections, Y, X and W.

If the high speed route is cleared when the locomotive passes Z', all sections of the ramp rail will be energized so that the locomotive monitor will derive a rise in 120 speed limit, as indicated by the rising curve 434^a, co-extensive with the entire ramp rail Y X W, thereby acquiring the headway indicated by the declining speed-limit curve 434, which will permit the train to 125 pass Z at high speed over the high speed route. The three sections of the ramp rail are energized through the following connections with the battery 455 which has its positive pole grounded on the track rails; 130

from the negative pole of the battery 455 through the wire 437 and thence through three contacts controlled by the high speed signal to the three wires 438, 439 and 440, and through these wires respectively to the ramp sections W, X and Y.

If the medium speed route is cleared when the locomotive passes Z', only the sections X and W of the ramp rail will be energized, so that the rise in the speed limit as the locomotive wipes over the ramp will be only co-extensive with these sections, as indicated by the rising curve 435^a, which imparts the headway shown by the declining speed limit 435, permitting the train to pass Z at a medium speed to take the medium speed route. In this instance, the ramp sections X and W will be energized through contacts closed by the medium speed signal and serving to connect the wire 437 with the wires 439 and 438 leading respectively to these ramp sections.

If the low speed route is cleared when the train passes Z', only the ramp section W will be energized, and the consequent rise in speed limit will be only co-extensive with this ramp section, as indicated by the rising limit curve 436^a, which results in a headway limit 436, permitting the locomotive to pass Z at a low speed to take the low speed route. In this instance, the ramp section W is energized by the contact controlled by the low speed semaphore which connects the wire 437 with the wire 438 leading to this ramp section.

The speed limit curves 404, 405, 408, 434, 435 and 436 may be taken to represent the speed limits imposed by the stop weight 371, it being understood that a warning limit curve, which has not been shown, exists in fact underneath each of these stop-limit curves, so that the engine man will always receive a warning before the speed of his vehicle exceeds the stop limit.

When the warning weight 370 is thrown cut, it opens the following circuit: from one pole of the locomotive battery 409 through the wire 410, monitor casing, main shaft and warning weight 370, and thence through the upper contact ring, wire 372, signal magnet 411 and connecting wire back to the opposite pole of the battery. When the magnet 411 is de-energized, it gives the warning signal. When the stop weight is thrown cut, it opens the following circuit: from one pole of the locomotive battery 409 through the wire 410, monitor casing and main shaft, stop weight 371, lower contact ring, wire 373, stop magnet 412 and connecting wire back to the opposite pole of the battery. When the magnet 412 is de-energized, it releases its armature to open the service vent-valve connected therewith, thus venting the brake pipe.

Although I have herein shown and de-

scribed only one form of apparatus and system embodying my invention, it is understood that various changes and modifications may be made therein within the scope of the appended claims without departing from the spirit and scope of my invention.

Having thus described my invention, what I claim is:

1. In combination, a railway vehicle, means thereon arranged to change gradually towards an ultimate condition, vehicle-governing apparatus controlled by said means, devices of different lengths located at intervals in the trackway, and means on the vehicle co-operating with said trackway devices for restoring the first-mentioned means away from said ultimate condition to a variable degree dependent upon the length of the trackway device.

2. In combination, a railway vehicle, a main traveller thereon connected with a wheel of the vehicle and arranged to move gradually toward an ultimate position in accordance with the progress of the vehicle along the track, vehicle governing apparatus controlled by said traveller, a resetting traveller, means for connecting said resetting traveller with a wheel of the vehicle to restore said main traveller a variable distance away from said ultimate position depending upon the distance through which the vehicle moves while the resetting traveller is connected with the wheel of the vehicle, and devices of variable length located in the trackway for causing operation of said means.

3. Railway traffic controlling apparatus comprising means on a vehicle arranged to change gradually towards an ultimate condition, vehicle governing apparatus controlled by said means, mechanism operated by the running gear of the vehicle for restoring said means away from its ultimate condition, and devices located in the trackway for controlling said mechanism.

4. Railway traffic controlling apparatus comprising means on a vehicle arranged to change gradually towards an ultimate condition, vehicle governing apparatus controlled by said means, mechanism operated by the running gear of the vehicle for restoring said means away from its ultimate condition, said mechanism including a normally inoperative clutch and means including devices located in the trackway for rendering said clutch operative.

5. Railway traffic controlling apparatus comprising means on a vehicle arranged to change gradually towards an ultimate condition, vehicle governing apparatus controlled by said means, mechanism operated by the running gear of the vehicle for restoring said means away from its ultimate condition, said mechanism including a normally inoperative clutch and a magnet

- arranged when energized to render said clutch operative, and means including devices located in the trackway for energizing said magnet.
- 5 6. Railway traffic controlling apparatus comprising means on a vehicle arranged to change gradually towards an ultimate condition, vehicle governing apparatus controlled by said means, mechanism operated by the running gear of the vehicle for restoring said means away from its ultimate condition, whereby the degree of restoration will depend on the distance of vehicle travel during which the restoration is in effect, 10 and devices of different lengths located in the trackway for governing said mechanism.
- 10 7. Railway traffic controlling apparatus comprising means on a vehicle arranged to change gradually towards an ultimate condition, vehicle governing apparatus controlled by said means, mechanism operated by the running gear of the vehicle for restoring said means away from its ultimate condition, said mechanism including a normally inoperative 15 clutch and a magnet arranged when energized to place the clutch in operative condition, and means including devices of different lengths in the trackway for energizing said magnet.
- 20 8. Railway traffic controlling apparatus comprising trackway sections differing in length, means on a vehicle arranged to change gradually toward an ultimate condition in accordance with the progress of the vehicle along the track, vehicle governing apparatus controlled by said means, restoring devices for said sections the length of each device being a fixed fraction of the length of the associated section, and mechanism controlled by each of said devices for restoring said means away from ultimate condition to a variable degree depending on the length of the device.
- 25 9. Railway traffic controlling apparatus comprising trackway sections differing in length, means on a vehicle arranged to change gradually toward an ultimate condition in accordance with the progress of the vehicle along the track, vehicle governing apparatus controlled by said means, restoring devices for said sections the length of each device being a fixed fraction of the length of the associated section, normally 30 inoperative mechanism on the vehicle actuated by the running gear for restoring said means away from ultimate condition to a variable degree depending upon the distance of vehicle travel in which the mechanism is operative, and means controlled by said trackway devices for placing said restoring mechanism in operative condition.
- 35 10. Railway traffic controlling apparatus comprising means on a vehicle arranged to change gradually towards an ultimate condition, vehicle governing apparatus con- 35 trolled by said means, mechanism operated by the running gear of the vehicle for restoring said means away from its ultimate condition, and devices located in the trackway and controlled by traffic conditions in advance for controlling said mechanism.
- 40 11. Railway traffic controlling apparatus comprising means on a vehicle arranged to change gradually towards an ultimate condition, vehicle governing apparatus controlled by said means, mechanism operated by the running gear of the vehicle for restoring said means away from its ultimate condition, and devices of different lengths located in the trackway and controlled by 45 traffic conditions in advance for controlling said mechanism.
- 45 12. Railway traffic controlling apparatus comprising means on a vehicle arranged to change gradually towards an ultimate condition, vehicle governing apparatus controlled by said means, mechanism operated by the running gear of the vehicle for restoring said means away from its ultimate condition, a restoring device located in the trackway and made up of two sections in tandem controlled respectively by traffic conditions in two portions of track ahead of the device, and means controlled by said device for rendering said mechanism operative for a shorter or a longer interval of vehicle travel according as one or both of said portions of track are clear.
- 50 13. Railway traffic controlling apparatus comprising trackway blocks differing in length, means on a vehicle arranged to change gradually toward an ultimate condition in accordance with the progress of the vehicle along the track, vehicle governing apparatus controlled by said means, a restoring device for each block having two sections in tandem the length of the first section being a fixed fraction of the length of the associated block and the length of the second section being the same fraction of the length of the block next in advance, the first section being controlled by traffic conditions in the associated block and the second section by traffic conditions in the block next in advance, and mechanism on the vehicle controlled by each of said devices for restoring said means away from ultimate condition to a variable degree dependent upon the effective length of the device.
- 55 14. Railway traffic controlling apparatus comprising trackway blocks differing in length, means on a vehicle arranged to change gradually toward an ultimate condition in accordance with the progress of the vehicle along the track, vehicle governing apparatus controlled by said means, a restoring device for each block having two sections in tandem the length of the first section being a fixed fraction of the length of the associated block and the length of the sec- 60 65 70 75 80 85 90 95 100 105 110 115 120 125 130

- ond section being the same fraction of the length of the block next in advance, means for making the first section of each device effective when the associated block is unoccupied and the second section effective when the associated block and the block next in advance are unoccupied, and mechanism on the vehicle controlled by each of said devices for restoring said means away from ultimate condition to a variable degree dependent upon the effective length of the device.
15. Railway traffic controlling apparatus comprising a single track over which traffic moves in both directions, two sets of track-way devices for controlling vehicles moving in opposite directions respectively, two receiving members on a vehicle for co-operation with said two sets of devices respectively, a single mechanism on said vehicle controllable by either of said receiving members, two contacts attached to the vehicle and connected with said two receiving members respectively, a movable element on the vehicle connected with said mechanism, and a part driven by the running gear of the vehicle and frictionally engaging said movable element to cause the latter to co-act with one of said contacts or the other according as said vehicle is moving forward or backward.
20. 16. Railway traffic controlling apparatus comprising means on a vehicle arranged to change gradually toward an ultimate condition, vehicle governing apparatus controlled by said means, mechanism on the vehicle for restoring said means away from its ultimate condition, a single track over which traffic moves in both directions, two sets of track-way devices for traffic in the two directions respectively and each adapted to control said restoring mechanism, and means on the vehicle for placing said mechanism under the control of one of said sets of trackway devices or the other according as the vehicle is moving in one direction or the other.
25. 17. Railway traffic controlling apparatus, comprising contact rails of different lengths located in the trackway, and governing mechanism on a vehicle controlled by said rails and responsive to different degrees to rails of different lengths.
30. 18. Railway traffic controlling apparatus

comprising contact rails of different lengths located in the trackway, and governing mechanism on a vehicle driven by the running gear of the vehicle and controlled by said contact rails.

35. 19. Railway traffic controlling apparatus comprising controlling devices of different lengths located in the trackway, and governing mechanism on a vehicle driven by the running gear of the vehicle and controlled by said devices.

40. 20. Railway traffic controlling apparatus comprising controlling devices of different lengths located in the trackway, governing means on a vehicle arranged to change gradually towards an ultimate condition, and mechanism on said vehicle operated by the running gear thereof and controlled by said trackway devices for restoring said means away from its ultimate condition.

45. 21. In combination, a trackway divided into blocks differing in length, a trackway device for each block the length of which is a fixed fraction of the length of the block, and governing mechanism on a vehicle operated by the running gear of the vehicle and controlled by said trackway devices.

50. 22. Railway traffic controlling apparatus comprising a trackway divided into blocks differing in length, governing means on a vehicle arranged to change gradually towards an ultimate condition in accordance with the progress of the vehicle along the track, and mechanism including apparatus on the vehicle and co-operating devices of different lengths located in the trackway for restoring said means away from its ultimate condition.

55. 23. Railway traffic controlling apparatus comprising a trackway divided into blocks differing in length, governing means on a vehicle arranged to change gradually towards an ultimate condition in accordance with the progress of the vehicle along the track, and a trackway located adjacent the entrance end of each block for causing said means to be restored away from its ultimate condition to a variable degree depending on the length of the block.

60. In testimony whereof I affix my signature.

ALBERT V. T. DAY.
